UNITED STATES PATENT OFFICE.

DANIEL M. COOPER, OF ROCHESTER, NEW YORK, ASSIGNOR TO AMERICAN LAUNDRY MACHINERY COMPANY, OF CINCINNATI, OHIO, A CORPORATION OF OHIO.

DRIER.

1,137,306.

Specification of Letters Patent. Patented Apr. 27, 1915.

Application filed November 14, 1912. Serial No. 731,265.

To all whom it may concern:

Be it known that I, DANIEL M. COOPER, of Rochester, in the county of Monroe and State of New York, have invented certain new and useful Improvements in Driers; and I do hereby declare the following to be a full, clear, and exact description of the same, reference being had to the accompanying drawings, forming a part of this specification, and to the reference numerals marked thereon.

My invention relates to driers, and more particularly to that class of machines embodying a rotating holder and means for discharging a current of heated air through the holder, such as are employed, in laundry drying plants and for similar purposes, and it has for its object to provide a simple construction involving a novel arrangement of parts by which the work may be performed quickly and efficiently.

A further object of my invention consists in the provision of a machine that is adapted to be converted from a vacuum operating drier into a pressure operating drier or vice versa according to the desire of the user.

To these and other ends the invention consists in certain improvements and combinations of parts all as will be hereinafter more fully described, the novel features being pointed out in the claims at the end of the specification.

In the drawings: Figure 1 is a view in end elevation of a machine constructed in accordance with a preferred embodiment of my invention; Fig. 2 is an elevation of the opposite end of the machine; Fig. 3 is a rear elevation; Fig. 4 is a longitudinal vertical sectional view; Fig. 5 is a transverse vertical sectional view; Fig. 6 is a sectional view on the line 6^a—6^a of Fig. 5; Fig. 7 is a transverse vertical sectional view of the lower part of a machine, embodying a modified arrangement of my invention; and Fig. 8 is a sectional view on the line 8^a—8^a of Fig. 7.

Similar reference numerals throughout the several figures indicate the same parts.

In the present embodiment, the casing, which is preferably formed of separable sections, comprises an upper portion 1, lower portion 2, and a rear portion 3, which are suitably bolted together, and are constructed

as shown in order to enable the machine to be more readily handled during transportation, preparatory to being assembled. Journaled within the casing is a rotary holder, preferably in the form of a perforate cylinder designated generally at 4 and mounted in the bearings 5 at the opposite ends of the casing.

Arranged at the rear of the casing in the portion 3 thereof, is a heating chamber which is separated from the front part of the machine by a partition 6, and contains a plurality of heating coils 7 adapted to receive steam or other heating medium, while 8 designates heating coils, disposed near the top of the casing and separated from the drying cylinder by means of the circular wall 9 which extends downwardly to a point substantially above the bottom of the casing as shown in Fig. 5.

10 is a passage way formed at the top of the casing and connecting the heating chamber with the rotating cylinder, the heated air being directed downwardly into the cylinder by the curved partition 11 which extends from the top of the casing to a point immediately adjacent to the top of the cylinder.

Arranged beneath the drying cylinder is means for effecting movement of the heated air, and to this end, there are preferably provided a pair of suction fans 12 mounted on the shaft 13. The fans include casings 14 having outlets 15 connecting with the passage or conduit 16, the latter being open at one end and in communication with the atmosphere, as shown in Fig. 2.

17 designates an additional passage conduit separated from the passage 16 by the inclined wall 18, the passage 17 being in communication with the atmosphere and with the bottom of the heating chamber and separated from the front part of the casing by means of the wall 19.

In the operation of the machine, a partial vacuum is created within the drying cylinder, the air being drawn through the passage 17 to the bottom of the heating chamber, as shown by the arrows in Fig. 2 thence upwardly to a point above the top of the drying cylinder, and from there downwardly, transversely of the cylinder and into the suction fans, from which it passes out

through the conduit 16. Access may be had to the bottom of the casing through the hinged door 20.

21 designates a door leading to the drying cylinder, the latter being provided with the hinged portion 22 through which the clothes or material to be dried may be inserted.

23 is an emergency door at the top of the casing which is provided to obviate any danger from an explosion within the cylinder, such as may happen in treating clothes that have been dry cleaned. The fans may be operated in any suitable manner as by means of a motor 24, connected with the shaft 13 by the belt 25. The shaft 13 is provided with fast and loose pulleys, and 26 is a belt shifter for moving the belt from one to the other. The drying cylinder or holder is operated by means of a motor 27 which is connected through a suitable train of gearing with a gear wheel 28 fixed upon a stub shaft 29 which is carried by the cylinder.

In some instances, it is preferred to employ a pressure of air through the drying cylinder instead of creating a vacuum by suction, and to this end, the machine is arranged so that it may readily be adapted to either one system or the other. When the heated air is to be forced through the drying cylinder by pressure, the parts are arranged as shown in Figs. 7 and 8, the fan casings 30 being turned so as to communicate with passages 31 which lead to the bottom of the heating chamber.

32 is a passage connecting the bottom of the cylinder with the atmosphere, and separated from the fans by means of the inclined wall 33.

34 is a partition connecting the wall 33 with the upwardly extending front wall 35, whereby the air is forced directly from the bottom of the cylinder into the passage 32. With this form of the invention, the air is drawn from the atmosphere first to the fans, and forced thence through the passages 31 to the heating chamber. It is then carried under pressure, upwardly to the top of the casing, and downwardly through the drying cylinder, being discharged at the bottom into 50 the outlet passage 32.

I claim as my invention:

1. The combination with a casing, of a holder journaled in the casing, a heating chamber arranged in the casing, and means disposed beneath the holder at the forward part of the casing and connected with a source of air supply for effecting movement of air through the heating chamber, and through the holder in a direction trans-

versely thereof.

2. The combination with a casing, of a holder journaled in the casing, a heating chamber arranged in rear of the holder, a source of air supply connected with the heating chamber, and means arranged be-

neath the holder at the forward part of the casing for effecting movement of the heated air therethrough.

3. The combination with a casing, of a holder journaled in the casing, a heating chamber, and means arranged beneath the holder at the forward part of the casing for causing a current of air to pass successively through the heating chamber, and through the holder in a direction transversely thereof.

4. The combination with a casing, of a holder journaled in the casing, and means arranged beneath the holder at the forward part of the casing for causing a current of air to pass through the holder in a direction transversely thereof.

5. The combination with a casing, of a holder journaled in the casing, a heating chamber in rear of the holder, and means arranged beneath the holder at the forward part of the casing for causing a current of air to pass upwardly through the heating chamber and thence downwardly through the holder in a direction transversely of its 90 rotating axis.

6. The combination with a casing, of a holder journaled in the casing, a heating chamber in rear of the holder, and a fan disposed beneath the holder at the forward 95 part of the casing and adapted to draw air through the heating chamber and thence through the holder.

7. The combination with a casing, of a holder journaled in the casing, a heating chamber in rear of the holder, suction means arranged beneath the holder and in front of said heating chamber, and an air supply conduit leading to the chamber, the latter being connected with the top of the 100 holder by a passage leading thereto.

8. The combination with a casing comprising separable front and rear sections, of a rotary holder journaled in one of the parts, a pump disposed beneath the forward 110 part of the holder, air conduits arranged beneath the rear part of the holder and separated therefrom, a heating chamber arranged in the rear section of the casing, the heating chamber and holder being connected 115 by passages extending through the casing.

9. The combination with a casing, of a rotary holder journaled in the casing, a heating chamber in rear of the holder and communicating therewith by a passage leading to the top of the holder, suction means arranged beneath the holder at the forward part of the casing and communicating with the bottom thereof, and an air supply conduit leading to the heating chamber.

10. The combination with a casing, of a holder journaled in the casing, a heating chamber arranged in the casing, and means disposed beneath the holder in front of the 130

heating chamber and connected with a source of air supply for effecting movement of air through the heating chamber and through the holder in a direction transversely thereof.

11. The combination with a casing, of a holder journaled in the casing, a heating chamber in rear of the holder, and means arranged beneath the holder in front of said

heating chamber connected with a source of air supply for effecting movement of air through the heating chamber, the latter being connected with the top of the holder by a passage leading thereto.
